UNITED STATES PATENT OFFICE

136,391

DESIGN FOR A PLAQUE OR SIMILAR ARTICLE

Harry B. Tabor, Everett, Mass.

Application June 17, 1943, Serial No. 110,471

Term of patent 3½ years

To all whom it may concern:

Be it known that I, Harry B. Tabor, a citizen of the United States of America, residing at Everett, in the county of Middlesex, in the Commonwealth of Massachusetts, have invented a new, original, and ornamental Design for a Plaque or Similar Article, of which the following is a specification, reference being had to the accompanying drawing, forming a part thereof, in which Figure 1 is a front elevational view of my plaque or similar article, and Figure 2 is an end view thereof.

I claim:

The ornamental design for a plaque or similar article, substantially as shown.

HARRY B. TABOR.
